HALLOCK WARDMAN, OF RACINE, WISCONSIN, ASSIGNOR TO J. MOORES JONES, OF RACINE, WISCONSIN.

VISE.

1,193,090.

Specification of Letters Patent.

Patented Aug. 1, 1916.

Application filed December 27, 1915. Serial No. 68,646.

To all whom it may concern:

Be it known that I, HALLOCK WARDMAN, a citizen of the United States, and resident of Racine, in the county of Racine and State of Wisconsin, have invented new and useful Improvements in Vises, of which the following is a description, reference being had to the accompanying drawings, which are a part of this specification.

10 The invention relates to vises.

The invention is designed more particularly to provide a vise in which the movable jaw member is readily and quickly clamped in position and the clamping face of which member may be disposed at an angle to the clamping face of the fixed jaw member for securing work of irregular shape in the vise.

The invention is further designed to provide a vise in which the movable jaw member is slidably mounted upon the fixed jaw and adapted to be secured thereto in different positions of adjustment, the securing means co-acting with the movable jaw member to constantly exert a force upon the face 25 of said jaw member downwardly and below its center of gravity so as to prevent any tendency of the movable jaw member to tip upon the fixed jaw member.

The invention is further designed to provide a new and improved form of vise.

The invention consists in the several features hereinafter set forth and more particularly defined by claims at the conclusion hereof.

35 In the drawings: Figure 1 is a view of the device, parts being broken away and parts being shown in section; Fig. 2 is a section taken on line 2—2 of Fig. 1; Fig. 3 is a section taken on line 3—3 of Fig. 1; Fig. 4 is a section taken on line 4—4 of Fig. 2.

The device consists in general of a fixed jaw member 5 and a movable jaw member 6 mounted on said fixed member, and means for clampingly locking the movable member 45 to the fixed member in different positions of adjustment to secure and clamp the work between the jaws 7 and 8 respectively of said members.

50 The fixed jaw member 5 comprises a base plate 9 provided with a longitudinally extending inverted T-shaped guideway 10 extending centrally through said plate for a portion of its length and opening as shown at 11 into the top of the plate. The upper 55 sides 12 of the inverted T-shape guide-way

are provided with corresponding series of rack teeth 13 for purposes hereinafter described. The jaw 7 of the fixed jaw member extends upwardly and at right angles to the base 9 at one end thereof.

60 The movable jaw member comprises the jaw 8, and a supporting portion 14 slidably mounted upon the top of the base 9 and provided with a vertically extending slot 15 having a concavely curved inclined face 16 at one end thereof.

65 The means for securing the movable member to the fixed member comprises means for engaging the rack teeth in the slot in the base member and means for wedging said 70 rack engaging means against the fixed member to thereby wedge or clamp the movable jaw member to said fixed jaw member and to move said movable jaw member forwardly 75 to clamp the work between it and the fixed jaw.

The means for engaging the rack teeth of the base member comprises an inverted T-shaped member 17 having a series of teeth 18 on the upper sides 19 of the flanges of the T, which teeth are adapted to register with the teeth 13 of the guide-way 10. The width of the flanges of the T are less than the width of the flanges of the guide-way so that 80 there is sufficient clearance between the bottom 20 of the inverted T and the bottom 21 of the guide-way to permit said inverted T-shaped locking member 17 to be moved downwardly to disengage its teeth from the teeth in the base of the fixed jaw member so that 85 it may be moved within the guide-way in the base to various positions of adjustment and be brought into engagement with said teeth when desired. The upper end of the inverted T-shaped member 17 is provided 90 with an enlarged eyed portion 22 angularly disposed with respect to the horizontal and the angularly extending eye 23 of which is 95 interiorly threaded.

100 The means for securing the rack engaging means in clamping position to thereby secure the movable jaw member in position on the fixed jaw member comprises a screw shaft 24 in threaded engagement with the threaded eye 23 and provided with a hand wheel 25 at the upper end thereof and a spherically convex end 26 at the lower end of said rod which spherically convex end is adapted to engage with the concavely 105 curved inclined side 16 of the slot 15 in the 110

movable jaw member. The axis of the screw shaft 24 is disposed in a line which passes down through the center of mass of the movable jaw member and consequently below the center of gravity of said member so that its end 26 will exert at all times a downward pressure against the side 16 of the slot 15 as indicated by the arrow shown in Fig. 4 which force will counteract any force acting on the face of the movable member having a tendency to lift said jaw member from engagement with the top of the base of the fixed jaw member. Consequently when the movable jaw member is brought to the desired position upon the base of the fixed jaw member and the screw shaft 24 is brought into the clamping engagement with the inclined side of the slot 15 there will be no tendency of the movable jaw member to tilt with respect to the fixed jaw member and the jaws 7 and 8 will therefore always remain at right angles to the horizontal and thus efficiently clamp the work disposed between them.

25. The concavely curved surface 16 of the slot 15 permits the movable member 6 to be moved so that the face of the jaw 8 is angularly disposed with respect to the face of the jaw 7 without shifting the locking means from the movable member as the end 26 of the screw shaft 24 is adapted to contact at any point with the concavely curved surface 16.

It will be noted that the inclined surface 35 16 of the movable jaw member contacting with the end 26 of the screw shaft 24, when said shaft is brought down into engagement with the surface through the turning of the handle 25, wedges up and exerts a force to 40 counteract the downward force due to the movement of the screw shaft 24 against it and by this wedging action moves said shaft upwardly and consequently moves the T-shaped member 17 in which the shaft has 45 its bearing upwardly thereby causing the teeth 18 on said locking member 17 to engage the teeth 13 in the base 9 of the fixed jaw member and be there secured in locking position so that any tendency for vertical or lateral movement of the movable jaw member 50 with respect to the base of the fixed jaw member will be prevented and the material disposed between the jaws of said members will consequently be securely clamped in position, whether the face of the movable jaw member is disposed parallel to the face of the fixed jaw member or at an angle thereto.

55. The operation of the device is as follows:—Stock, such as the round member 27, is placed so as to abut against the clamping face of the fixed jaw member 7. The screw shaft 24 is rotated by turning the handle 25 so that its end 26 is held away from engagement with the movable jaw member 6 under which condition its inverted T-shaped

lower end will be freely slidably movable within the guide-way 10 in the base 9 of the fixed jaw member. Under these conditions the movable member 6 together with the locking means including the inverted T-shaped member 17 is moved forwardly along the base 9 until the clamping faces of its jaw 8 engages with the other side of the work 27. Then the hand wheel 25 is turned so as to move the shaft 24 downwardly to bring its end 26 into engagement with the inclined side 16 of the movable member 6 and after it is brought into engagement a further turning of the wheel moves the movable jaw member 6 forwardly against the work and produces the wedging action before described and brings the lower toothed portion of the member 17 into locking engagement with the base 9 of the fixed jaw member and thus locks both of the jaws in gripping position.

The invention thus exemplifies a simple and efficient form of vise in which the movable member is pressed against the work and locked in position with respect to the fixed member by locking means having a wedging engagement with the movable member and a locking engagement with the base of the fixed member.

55. The invention is not to be restricted to the details of construction herein set forth, it being my intention to claim the invention as broadly as will be permitted by the state of the prior art.

What I claim as my invention is:—

1. In a vise, the combination of a fixed member comprising a clamping jaw and a base, a movable member comprising a clamping jaw and a base slidably mounted upon the base of the fixed member and angularly adjustable with respect thereto and provided with a slot having an inclined face at one end thereof, and locking means for securing said movable jaw in different positions of angular adjustment adjustably secured to the base and having wedging engagement with said inclined face.

2. In a vise, the combination with a fixed member comprising a clamping jaw and a base, a movable member comprising a clamping jaw and a base slidably mounted upon the base of the fixed member and angularly adjustable with respect thereto and provided with a slot having a concavely curved inclined face at one end thereof, and locking means for securing said movable jaw in different positions of angular adjustment adjustably secured to the base and having wedging engagement with said inclined face.

3. In a vise, the combination of a fixed member having a clamping jaw and a supporting base, a movable jaw member slidably mounted upon the top of said supporting base for movement toward or away from

- said fixed clamping jaw and at an angle with respect thereto and provided with a concavely curved inclined bearing surface, a rotatable screw shaft having a spherically convex end for wedging engagement with said bearing surface, and a locking member adjustably secured to the supporting base and having an inclined threaded bearing for said shaft.
- 10 4. In a vise, the combination of a fixed member having a clamping jaw and a supporting base, a movable jaw member slidably mounted upon the top of said supporting base for movement toward or away from said fixed clamping jaw and at an angle with respect thereto and provided with a concavely curved inclined bearing surface, a rotatable screw shaft having a spherically convex end for wedging engagement with 15 said bearing surface, and a locking member having a wedging engagement with said base and provided with an inclined threaded bearing for said shaft.
- 15 5. In a vise, the combination, with a fixed member comprising a clamping jaw and a base, a movable member comprising a clamping jaw and a base slidably mounted upon the base of the fixed member for movement toward or away from said fixed member and at an angle with respect thereto and provided with a concavely curved inclined bearing surface, and locking means adjustably secured to the base and having wedging engagement with said inclined face.
- 20 6. In a vise, the combination of a fixed member comprising a clamping jaw and a base provided with a guideway, a locking rack in the base on the upper side of said guideway, a movable member comprising a clamping jaw and a base slidably mounted upon the base of the fixed member and provided with a slot and an inclined bearing surface at one end thereof, a rotatable screw shaft for wedging engagement with said bearing surface, a locking member having a threaded bearing for said shaft disposed within the slot of said movable member and having an inverted T-shaped portion running in said guideway and provided with teeth for lockingly engaging said rack to clamp the movable jaw to the base when the screw shaft is in engagement with the bearing surface of the movable jaw.
- 25 7. In a vise, the combination, of a fixed member comprising a clamping jaw and a base provided with an inverted T-shaped guideway, a locking rack in the base on the upper side of said guideway, a movable member comprising a clamping jaw and a base slidably mounted upon the base of the fixed member and provided with a slot and an inclined bearing surface at one end thereof, a rotatable screw shaft for wedging engagement with said bearing surface, a locking member having a threaded bearing for said shaft disposed within the slot of said movable member and having an inverted T-shaped portion running in said guideway and provided with teeth for lockingly engaging said rack to clamp the movable jaw to the base when the screw shaft is in engagement with the bearing surface of the movable jaw.

In testimony whereof, I affix my signature, in presence of two witnesses.

HALLOCK WARDMAN.
